UNITED STATES PATENT OFFICE.

ALBERT LEHNHARDT, OF JERSEY CITY, NEW JERSEY.

DESIGN FOR A STOVE-BOARD.

SPECIFICATION forming part of Design No. 21,808, dated August 30, 1892.

Application filed July 21, 1892. Serial No. 440,824. Term of patent 3½ years.

To all whom it may concern:

Be it known that I, ALBERT LEHNHARDT, a citizen of the United States, and a resident of Jersey City, Hudson county, New Jersey, have 5 invented and produced a new and original Design for the Ornamentation of Stove-Boards and the Like, of which the following is a specification, reference being had to the accompanying drawing for a fuller understanding of the design.

The leading features of the design are an ornamental border A, a circular center-piece B within said border, and points C, of triangular form, arranged about and abutting on 15 said circular figure B, with their points directed toward said border. The border A comprises exteriorly a scalloped band a, and said border has interiorly an ornamental crenelated band a'. Between the bands a and a' of the border are ogive-shaped ornaments a², pointing outward and alternating with representations of clover-leaves a³ adjacent to the band a and pointed ornaments a⁴ adjacent to the band a'. At the respective rounded corners of the border are repre-

sentations of clover-blossoms a⁵. Within the center-piece B are the representations of four clover-blossoms b, with intertwined stems and leaves, and four quaterfoils or representations of four-leaved clovers b'. The center-piece B has a border b², on which are the representations of clover-leaves. On each of the four longer points C is a representation of a clover-blossom c with leaves, and the ground between the points C and within the border A is covered uniformly with representations of individual leaves e.

What I claim is—

The design for the ornamentation of a stove-board, herein shown and described, the same 40 comprising the border A, the center-piece B, and the points C, as set forth.

In witness whereof I have hereunto signed my name in the presence of two subscribing witnesses.

A. LEHNHARDT.
